MIRRORED MOLDING

Joseph Bezborodko, 629 Kappock St.,
New York, N.Y. 10463

Filed Feb. 22, 1973, Ser. No. 334,965

Term of patent 14 years

Int. Cl. D6—07

U.S. CL. D6—246

FIG. 1 is a front elevational view of a mirrored molding showing my new design, a portion thereof being broken away to indicate indeterminate length;

FIG. 2 is a top plan view;

FIG. 3 is a left side elevational view of the molding shown in FIG. 1;

FIG. 4 is a right side elevational view thereof;

FIG. 5 is a rear elevational view thereof; and

FIG. 6 is a bottom plan view.

I claim:

The ornamental design for a mirrored molding, substantially as shown and described.
